UNITED STATES PATENT OFFICE.

CHARLES A. NASH, OF SEATTLE, WASHINGTON.

INJECTOR FOR STEAM ENGINES.

1,417,853.

Specification of Letters Patent. Patented May 30, 1922.

Application filed December 10, 1920. Serial No. 429,687.

To all whom it may concern:

Be it known that I, CHARLES A. NASH, a citizen of the United States, residing at Seattle, in the county of King and State 5 of Washington, have invented certain new and useful Improvements in Injectors for Steam Engines, of which the following is a specification.

This invention relates to injectors for 10 steam engines the primary object being to provide an injector having independent steam and water ways which converge so as to commingle the water and steam prior to its entry into the steam boiler.

15 Another object of the invention is to provide a valve automatically operable by ingress of steam to simultaneously open communication through the steam and water ways, the valve being automatically closed 20 as soon as pressure of the steam is released. The above and other objects of this invention will be in part described and in part understood from the following description 25 of the present preferred embodiment of the invention taken in connection with the accompanying drawings, wherein:

Fig. 1, is a longitudinal sectional view of 30 an injector constructed in accordance with my invention showing the casting of the steam passageway in side elevation, and

Fig. 2, is a top plan view thereof showing the cleaning cap removed, taken on the line 2—2 of Fig. 1.

In the drawings, a steam injector pipe 3 35 is provided which may be of a cylindrical or other desired configuration being provided at one end with a steam inlet 4. A steam mount 5 is formed on the inner periphery of the pipe and extends upwardly 40 into close proximity with the upper inner periphery of the pipe, leaving only a relatively narrow passage way 6 for the steam between the apex of the mount and the inner periphery of the pipe. A water inlet pipe 45 7 is detachably mounted in the pipe 3 and communicates with a water inlet opening 8, which extends through the mount 5 and terminates in a bore 9 which is formed in the pipe.

50 The bore 9 extends vertically through the pipe 3 and has slidably mounted therein a piston valve 10. The piston valve is preferably cylindrical in shape and is reduced midway its ends, as indicated at 11, to provide 55 an annular chamber which is to communicate with the water opening 8 to per-

mit the passage of water through said bore and into a water way 12, which latter extends longitudinally through the pipe 3. The upper end of the valve is normally held in engagement with a valve seat. The valve seat in this instance consists of a horse shoe shaped casting 6' which issues from the wall of the bore 9. The constricted open end of the casting communicates with the passageway 6. A clean-out cap 13 is threaded in the bore 9 above the casting 6'. Removal of this cap permits the bore or valve to be cleaned or otherwise attended to when desired. 70

The valve 10 is normally held in a closed position by a coil spring 14, which is mounted in a chamber 15, the latter being detachably carried by the pipe 3 directly below the bore 9. This chamber comprises 75 a collar, the lower end of which has a closure 16 mounted thereon, the said closure being provided with a screw threaded opening through which a threaded shank 17 extends. One end of the shank is provided with a 80 cup 18, which is mounted within the chamber 15 and receives the lower end of the spring 14. The lower or outer end of the shank has a head 19 formed thereon by which the shank may be conveniently 85 turned. Preferably the shank is engaged to the cup 18 by a swivel connection and is held from casual displacement in the closure 16 by means of a jam nut 20.

A wall 21 is formed in the pipe 3 and 90 extends longitudinally through the latter so as to provide the water way 12 on one side and a steam way 22 on the opposite side. The said wall has its inception at the bore 9 and gradually tapers to a point 23, the 95 latter extending into a tapering passageway 24, hereinafter referred to as the mixing chamber. Upon reference to Fig. 1 of the drawings, it will be noted that the passageways 12 and 22 are of an arcuate configuration and the outlet ends thereof are relatively narrow. Moreover, the passageway or mixing chamber 24 likewise tapers, whereby the water and steam will be thoroughly mingled and projected in a concentrated jet through the outlet end of the pipe 3 and into the boiler. It will be noted 100 that the outlet end of the pipe 3 is provided with a semi-spherical recess 25 to provide a relatively large pocket adapted for the 110 reception of steam, which may back from the boiler.

From the above it will no doubt be obvious that steam in passing through the inlet 5 and passage 6 will cause the valve 10 to be pressed downwardly against the resistance of the spring 14 thereby opening communication between the water opening 8 and water way 12, as well as between the steam inlet 4 and steam way 22. The steam and water are mingled in the chamber 24 and projected therefrom into the boiler in a manner above stated. The tension of the spring 14 may be adjusted through the medium of the shank 17 so as to regulate the pressure of the steam. The device may be quickly assembled and applied to standard types of boilers and may also be quickly dismembered for repair purposes if necessary.

What is claimed is:

- 20 1. An injector for steam boilers including an injecting pipe having steam and water inlets, a valve in the path of said inlets, said valve being automatically opened by the influx of steam to permit simultaneous passage of steam and water through said pipe.
- 25 2. An injector for steam boilers including

an injecting pipe having steam and water inlets and independent steam and water ways through a portion of the length of 30 the pipe, said ways converging to mingle the steam and water prior to their entry into the boiler, and a valve mounted in said pipe to normally close communication through said ways but being automatically 35 opened by ingress of steam to open communication through said ways.

3. An injector for steam boilers including an injecting pipe having steam and water inlets and steam and water ways for communication with said inlets, a valve normally closing communication between said inlets and ways, said valve being automatically 40 opened by ingress of steam of a predetermined pressure through the steam inlet, a spring to automatically close said valve upon the reduction of pressure of 45 said steam, and means to regulate the tension of said spring substantially as described.

CHARLES A. NASH.
